UNITED STATES PATENT OFFICE

EDWIN L. GRAUEL, OF CINCINNATI, OHIO

MATCH PACKAGE

Application filed October 31, 1930. Serial No. 492,551.

My invention relates to match receptacles and packages in which matches, usually safety matches, are retained with their heads enclosed and with their ends extending from the packages, and in which strips or areas of fulminate are arranged at the outlet orifices in the packages so that the matches will be ignited as they are withdrawn.

In my application Serial No. 483,049, filed September 19, 1930, I have disclosed a match package in which an inner fold composed of a single sheet of cardboard or paper is provided, with bands of fulminate arranged at the ends of the folds. The folds are bent over until the walls lie in parallel alignment, and a cover member is applied which holds the matches within the folded piece and makes an air-tight package therewith. While the match package disclosed in my aforesaid application will be found to be entirely serviceable without the outer metallic cover member disclosed, since no particular means are shown in this co-pending case for creating tension at the outlet orifice of the package except the lips of the holder to prevent matches from falling out, it is an object of my present invention to provide a simple match package which may be employed entirely successfully without an outer holder.

In the construction of the package described herein, it is another of my objects to provide a package in which the portions of the package receiving the matches are so constructed that easy withdrawal of the matches is permitted without any tendency to stick within the package. This is particularly advantageous in the withdrawal of the end match, which, in my previous construction, occasionally caused some difficulty because of its tendency to stick within the package.

Another object is the provision of a match package composed of a blank or set of blanks which can be readily folded and assembled on automatic machinery.

A still further object is the provision of a match package in which the parts fit snugly together so that the package will be substantially fire-proof, thereby eliminating the

danger of any fire hazard in connection with the use of these packages.

Since in the production of match packages the cost of the materials employed is of great importance, it is a further object of my invention to provide blanks for forming the packages which can be cut economically from the sheets of inexpensive, flexible material, such as paper, from which the packages are made.

Referring to the drawings in which I have shown several preferred modifications of inner folders or blanks for match packages:

Figure 1 is a plan view of a cut and scored blank with the edges of the blank provided with indentations for retaining matches in spaced position within the package.

Figure 2 is a plan view of a blank provided with cut away portions providing an easy start in withdrawing the matches.

Figure 3 is a plan view of a different type of inner fold.

Figure 4 is a side elevation of a partially folded inner blank, with the position indicated in which the matches are inserted within the partially folded blank.

Figure 5 is a perspective view of a filled package.

Figure 6 is a perspective view of the inner fold of a package prior to its being folded over to enclose the matches.

Figure 7 is a perspective view of an outer cover member.

Figure 8 is a plan view of a one-piece blank forming the inner fold and outer cover.

Figure 9 is a plan view of the blank shown in Figure 8 partially folded up.

Figure 10 is a perspective view of the assembled box formed from the blanks shown in Figures 8 and 9, without the matches.

Figure 11 is a sectional view along the lines 11-11 in Figure 10, with the position of the matches indicated.

In Figure 1 I have shown a blank with sides 1 having zig-zag cut walls, and with score lines 2 at substantially the median line of the blank, which permits the sides to be folded over with the match heads held within the fold adjacent the area between the score lines 2-2. It will be noted that from the central

area of the blank the side walls incline upwardly and downwardly, and then flare outwardly to the end edges 3-3 of the blank. Along the narrowest portion of each side where the side walls start to flare outwardly, I provide score lines 4-4, and adjacent the outer of the score lines I provide areas 5 to which a coating of fulminate or other material to cause the ignition of the matches, is disposed. The end edges 3-3 are provided with serried indentations 6-6 which will, if desired, hold the shafts of the matches in separated condition.

In employing the inner folding member illustrated in Figure 1, the blank is first cut and scored and then ordinarily the bands 5 of fulminate are applied. The cutting and scoring and application of the fulminate may, however, be carried out with a single continuous operation. After the blank has been cut and scored and the fulminate has been applied and allowed to dry, the package is ready for receiving its matches, which ordinarily will be inserted within the package as indicated in Figure 4, by partially folding the blank along the lines 4-4, and then along the score lines 2-2 until the inner fold has assumed a V-shaped arrangement, at which time the matches are deposited in the partially folded member.

Referring to Figure 1, the outside of the blank or folding member is illustrated. In assembling this blank the end flaps of the blank are folded away from the position in which the blank is illustrated; then the side walls of the blank are also folded away from the position illustrated, and after the matches are inserted with their heads within the folded piece, the tension caused by the inner flaps bent along the score lines 4-4 will tend to hold the matches snugly in position. An outer wrapper 7, which is of slightly tapered shape and of suitable size to fit snugly about the inner folded member, may then be applied to the folded member to hold the package securely together. The outer cover may be formed of thin paper or other suitable material, and ordinarily will bear announcements or other suitable advertising or design material. Referring to the dotted lines 8 in Figure 1, it will be observed that by staggering blanks which are cut from a sheet there will be no waste material, due to the zig-zag shape of the sides of the blank.

In Figure 2 I have shown the blanks 1a provided as in Figure 1 with the score lines 2a-2a along the middle area of the package, and with the necks of the blanks forming the withdrawal orifice also provided with score lines 4a-4a. The portions of the blank which form the withdrawal orifice are provided with areas of fulminate indicated at 5a. The shape of the blank shown in Figure 2 is similar to the shape shown in Figure 1, excepting that instead of flaring outwardly

from the orifice necks of the blanks, the end portions are cut along inwardly tapering lines, such as are indicated at 9, so that when the blank is folded over to the position shown in Figure 6, it will be obvious that the end 70 matches within the receptacles will slide easily towards the withdrawal orifice.

In Figure 3 the blanks 1b-1b are shown with the usual intermediate score lines 2b-2b, and the orifice necks score lines 4b-4b. 75 Areas of fulminate 5b-5b are applied in the usual manner, and the end infolding flaps are cut all different lengths so that one end 3b will have an inwardly folding flap of normal length and the other end 3c will be cut off, 80 providing clearance space. When the blank shown in Figure 3 is folded over to enclose the matches, an easy sliding space permitting the withdrawal of the matches toward the withdrawal orifice will be provided because of the cut away end 3c.

It will, of course, be entirely feasible to provide the outer closure member by providing extending flaps from the main bodies of the cartons which will fold over and provide a completely enclosing outer wrapper, and in order to illustrate such a modification, reference is made to Figures 8 to 11.

In Figure 8 the blank has side walls 1c-1c with score lines 2c-2c. End flaps 3c-3c are provided articulated to the side flaps with score lines 4c-4c. Fulminate is applied to one side and one flap 3c, as indicated at 5c-5c. In assembling the package made from a single blank, any desired fairly stiff 100 paper may be used.

Extending from one side of one of the sides 2c there is an articulated portion 10, and to it is articulated a wall 11 which in turn has an articulated portion 12 at its opposite side to which is articulated an outer wrapper sheet 13.

At one of its end edges the wall 10 has an articulated bottom closure flap 14. Referring to Figure 9, the first step in assembling the blank is to fold the side walls 1c-1c into parallel alignment with the flaps 3c bent also into parallel alignment. Next the blank is folded laterally along the score lines of the portions 10, and the wall 11 is folded into 115 alignment with the side 1c. The closure flaps 13 and 14 are then folded and sealed, making a package in which the matches will be retained so that they will not tend to drop out, and so that the start to withdraw them 120 will be easy.

The packages when completed will be substantially weather-proof and fire-proof. The matches being withdrawn in alignment with their length will have no tendency to have their heads broken off so that there will be a fire hazard, due to breaking off the burning heads of the matches. Since the outer wrapper fits snugly about the inner fold, the package will be substantially air- 200

tight, so that even if the exposed ends of the shanks of the matches are lighted, all that will happen will be that the ends will burn down as far as the necks of the withdrawal orifice, where, due to lack of air, their burning will be extinguished.

Since the igniting heads of the matches require a greater width than the exposed ends, the package is of slightly tapered shape, which is advantageous because it enables the outer wrapper to fit snugly down with a sliding fit over the inner folded blank, and variations in the size of the outer wrapper, of the blank, and of the matches, will still permit the package to be assembled in air-tight, snug-fitting condition. Because of the double fold of the inner flap, tension is exerted at the neck of the withdrawal orifice, and there will be no chance for matches falling out of the package once they are manually withdrawn.

Having thus described my invention, what I claim as new and desire to secure by Letters Patent, is:—

1. A match package comprising in combination with a row of matches having their heads retained within the package and their ends extending therefrom, an inner blank of flexible material having a folded flap extending within the package and bearing against the sides of the matches, said package having a withdrawal orifice with striking substance arranged adjacent said orifice to ignite the heads of the matches with the withdrawal thereof from the package, said flap having cut away portions to permit an easy start in the withdrawal of matches from the package.

2. A match package comprising in combination with a row of matches having their heads retained within the package and their ends extending therefrom, an inner blank of flexible material having a folded flap extending within the package and bearing against the sides of the matches, said package having a withdrawal orifice with striking substance arranged adjacent said orifice to ignite the heads of the matches with the withdrawal thereof from the package, said flap having cut away portions to permit an easy start in the withdrawal of end matches from said package.

3. A match package having a withdrawal orifice and with matches arranged with their ends extending through said orifice and with their heads within the package, means for igniting the heads arranged adjacent said orifice to contact with said heads during withdrawal of the matches, and means within the package for preventing the matches from dropping out, said means comprising a flap articulated to said package, said flap having cut away portions to permit a limited free movement of the matches prior to their withdrawal.

4. A match package comprising in combination with a row of matches, a folder for holding said matches with their heads adjacent the closed portion of said folder, and their other ends projecting free therefrom, said folder having a reentrant flap lying alongside said matches, said flap terminating short of the closed portion of said folder, and means encircling said folder to hold said folder closed.

5. A match package comprising in combination with a row of matches, a folder for holding said matches with their heads adjacent the closed portion of said folder, and their other ends projecting free therefrom, said folder having reentrant flaps lying alongside said matches, said flaps terminating short of the closed portion of said folder, and means encircling said folder to hold said folder closed.

6. A match package comprising in combination with a row of matches, a folder for holding said matches with their heads adjacent the closed portion of said folder, and their other ends projecting free therefrom, said folder having reentrant flaps lying alongside said matches, said flaps terminating short of the closed portion of said folder, and means encircling said folder to hold said folder closed, one of said flaps being shorter than the other whereby a graduated resistance is presented to the withdrawal of said matches.

7. A match package comprising in combination with a row of matches, a tapered folder for holding said matches, a tapered jacket for enclosing said folder and slidable thereon to positions of snug fit, means for striking said matches adjacent the lips of said folder, and means extending within said folder from the lips thereof, and beyond said striking means to provide a shoulder constituting a stop for a match head against the force of withdrawal, thus causing a rapid movement of the match head when passing the striking means.

8. A match package comprising in combination with a row of matches, a tapered folder of flexible fibrous material for holding said matches with their ends freely projecting, a tapered jacket for enclosing said folder and slidable thereon to positions of snug fit, return flaps on said folder, the line of articulation of said flaps forming a withdrawal orifice for said matches, the fold lines of said return flaps forming said orifice thereby reinforcing the lips of said orifice, and means for striking said matches located within said withdrawal orifice.

9. A match package comprising in combination with a row of matches, a tapered folder for holding said matches with their ends freely projecting, a tapered jacket for enclosing said folder and slidable thereon to positions of snug fit, reentrant flaps on said

5 folder, the line of articulation of said flaps forming a withdrawal orifice for said matches, said orifice having lips of double thickness, and means for striking said matches located on said flaps adjacent said withdrawal orifice, said flaps being less in length than the sides of said folder, whereby the ends of said flaps may be caused to engage the heads of said matches to inhibit the removal thereof.

10 10. A match package comprising in combination with a row of matches, a tapered folder for holding said matches, a tapered jacket for enclosing said folder and slidable thereon to positions of snug fit, reentrant flaps on said folder, the line of articulation of said flaps forming a withdrawal orifice for said matches, said orifice having lips of double thickness, and means for striking said matches located on said flaps adjacent said withdrawal orifice, said flaps being less in length than the sides of said folder, whereby the ends of said flaps may be caused to engage the heads of said matches to inhibit the removal thereof, one of said flaps being shorter than the other whereby a graduated resistance is presented to the withdrawal of said matches.
